UNITED STATES PATENT OFFICE.

ELIZABETH T. HINCKS, OF CAMBRIDGE, MASSACHUSETTS.

DESIGN FOR A CHILD'S OUTER GARMENT.

51,303.

Specification for Design.

Patented Sept. 25, 1917.

Application filed May 28, 1917. Serial No. 171,588. Term of patent 7 years.

To all whom it may concern:

Be it known that I, ELIZABETH T. HINCKS, a citizen of the United States, residing at Cambridge, in the county of Middlesex and State of Massachusetts, have invented a new, original, and ornamental Design for Child's Outer Garment, of which the following is a specification, reference being had to the accompanying drawing, forming part thereof.

Fig. 2 is a side elevation of child's outer garment, showing my new design.

I claim:

The ornamental design for a child's outer garment, as shown.

ELIZABETH T. HINCKS.

Witnesses:

EDWARD Y. HINCKS,
CLARA WHITE.
